US00D983037S

(12) **United States Design Patent** (10) **Patent No.:** **US D983,037 S**
(45) **Date of Patent:** **** Apr. 11, 2023**

(54) **CLOSURE**

(71) Applicant: **Silgan White Cap LLC**, Downers Grove, IL (US)

(72) Inventor: **Darren R. Neputy**, Palos Hills, IL (US)

(73) Assignee: **Silgan White Cap LLC**, Downers Grove, IL (US)

(**) Term: **15 Years**

(21) Appl. No.: **29/826,601**

(22) Filed: **Feb. 14, 2022**

Related U.S. Application Data

(62) Division of application No. 29/736,087, filed on May 27, 2020, now Pat. No. Des. 946,404, which is a division of application No. 29/611,386, filed on Jul. 20, 2017, now Pat. No. Des. 888,554.

(57) **CLAIM**

I claim the ornamental design for a closure, as shown and described.

DESCRIPTION

FIG. 1 is a front perspective view of a closure showing the new design;

FIG. 2 is a bottom perspective view thereof;

FIG. 3 is a front elevation view thereof, the right, back, and left views being a mirror image thereof;

FIG. 4 is a top plan view thereof; and,

FIG. 5 is a bottom plan view thereof.

The ornamental design which is claimed is shown in solid lines in the drawings. The broken lines are shown for the purpose of illustrating parts of the article that form no part of the claimed design.

1 Claim, 5 Drawing Sheets
